Primary Examiner — Paula Allen Greene(74) *Attorney, Agent, or Firm* — Ashkan Najafi(57) **CLAIM**

The ornamental design for a golf ball cremation urn, as shown and described.

DESCRIPTION

FIG. 1 is a front elevational view of a golf ball cremation urn showing my new design;

FIG. 2 is a right-side elevational view thereof;

FIG. 3 is a left-side elevational view thereof;

FIG. 4 is a top plan view thereof;

FIG. 5 is a front-left perspective view thereof;

FIG. 6 is a front-right perspective view thereof;

FIG. 7 is a rear elevational view thereof;

FIG. 8 is a bottom plan view thereof;

FIG. 9 is a bottom-right perspective view thereof; and,

FIG. 10 is a bottom-left perspective view thereof.

The broken lines immediately adjacent the shaded areas represent the bounds of the claimed design while all other broken lines are directed to environment; the broken lines form no part of the claimed design.
